UNITED STATES PATENT OFFICE.

GEORGE N. HEIN, OF SAN FRANCISCO, CALIFORNIA.

HYPODERMIC SYRINGE.

Application filed March 28, 1925. Serial No. 19,034.

To all whom it may concern:

Be it known that I, GEORGE N. HEIN, a citizen of the United States, residing at the city and county of San Francisco and State of California, have invented certain new and useful Improvements in Hypodermic Syringes, of which the following is a specification.

This invention relates to the class of hypodermic syringes, and especially to that type, such, for example, as those now well known as the "Luer", in which the piston corresponds to the diameter of the barrel and is self containing and packing in character, said piston being adapted to be fully withdrawn from the barrel to enable the solution to be poured into the upper or breech end of the barrel from a suitable container or pipette.

There are two methods of filling or partially filling a syringe. First, by fully projecting the piston in the barrel, then submerging the needle or nipple end of the barrel in the solution, and then drawing up the solution through the needle into the barrel by the retrogressive movement of the piston. Second, when using a syringe of the above mentioned type, that is, one having a piston so related to the barrel as to be self contained and packed, initially withdrawing said piston completely from the barrel so that the upper or breech end of the barrel is exposed, then pouring into said open end the charge of solution, and then reinserting the piston. The latter method is the one of choice as it insures safety from contamination of the sterile solution and is expeditious. This method is, however, open to the objection of lacking air venting and piston stabilizing as will be presently fully explained.

It is the object of the present invention to overcome this objection and to facilitate the filling of the syringe by providing means for expelling or venting the air from the barrel and for stabilizing the piston upon its entrance.

In order to more fully understand this object, it may be pointed out that in filling a syringe from the upper or breech end of the barrel, the instrument is usually held at a slight angle, the needle being in place, and, owing to its small opening, will cause sufficient capillary attraction to prevent the solution from escaping through it. But im-

mediately upon inserting the piston, the air filled space remaining between the upper limit of the solution and the top of the barrel will be compressed by the entering piston, and cause the solution to be ejected before the piston reaches a sufficient depth to allow the operator to invert the syringe, so that the air may interchange its position with the solution in the lower end of the barrel and then be ejected by a further insertion of the piston whereby the syringe is freed of air.

The present invention contemplates the immediate venting of this air from the upper or breech end of the barrel by the entering piston, which thus reaches a stable depth without producing any air pressure upon the solution. With this and other objects in view, the invention is herein described and illustrated, with the understanding that the form, proportion, and arrangement of the several parts may be varied, within the limits of the claims hereto appended, without departing from the spirit of the invention as set forth in said claims.

In order to comprehend the invention, reference should be had to the accompanying drawings, wherein:

Fig. 1 is a side elevation, partly in section, of a syringe showing one form of the contemplated improvement.

Fig. 2 is a longitudinal sectional view of the breech end of the syringe barrel.

Fig. 3 is a cross section on the line 3—3 of Fig. 2.

Fig. 4 is a longitudinal section of the breech end of a barrel showing a modification in the form of the air vent.

Fig. 5 is a cross section on the line 5—5 of Fig. 4.

Fig. 6 is a longitudinal section of the breech end of a barrel with a piston, in elevation, stabilized therein and showing another modification in the form of the air vent.

Fig. 7 is a longitudinal section of the breech end of a barrel, showing an associated entering piston and still another form of air vent.

Fig. 8 is a side elevation of a syringe partly in section showing still another modification of the air vent.

Fig. 9 is a view in elevation of the piston of Fig. 8 showing its venting groove.

Fig. 10 is a sectional view showing the

air vent of Fig. 1, but with the addition of a spring member pressing on the entering piston.

Fig. 11 is a sectional view showing a vent 5 in the wall of the piston and a spring member operating through said vent and pressing on the piston, said member also being associated with and serving to hold the finger grips.

10 Referring to Figs. 1, 2 and 3, the numeral 1 is the barrel of the syringe and 2 is the needle thereof. 3 is the finger grip. 4 is the piston and 4' is the packing.

15 In the inner surface of the breech end 15 of the barrel is made a longitudinally directed groove 5 which has a length sufficient to provide for such depth of entrance of the piston as will give stability to said piston. This groove opens out at the end of the 20 barrel, as shown in Figs. 1 and 2.

When, therefore, the piston having been withdrawn from the barrel, and the latter supplied with the solution, through the open end of the barrel up to about the inner end 25 of the groove 5 and the piston is then entered, as in Fig. 1, it will drive the air which lies between the upper limit of the solution and the end of the barrel, out through the vent groove 5, and said piston will reach a 30 stable position without having imposed any pressure upon the solution.

Referring to Figs. 4 and 5, it will be seen that the air vent assumes the form of a slot 6 passing through the wall of the barrel 35 extension.

In Fig. 6 the air vent 7 is in the form of a port opening through the barrel wall.

In Fig. 7 the air vent is in the form of a slightly enlarged interior annular passage 8 40 about the piston.

In Figs. 8 and 9 the piston end has a venting groove 9 which until the piston is stabilized leads the air past the packing.

In Fig. 10 the form of the vent 5 is the 45 same as the groove of Fig. 1, but in order to further insure the stability of the piston there is provided a spring wire 10 which clamps about the beaded head of the barrel and has an extension 11 which hooks into 50 the end of the groove 5 and presses on the piston.

In Fig. 11 a spring wire 12 has a bearing 55 end 13 which presses upon the piston through an air vent port 14 in the piston wall. This spring wire is connected with the annular hub 15 of the finger guards 16, which hub is slipped upon the barrel and abuts against the end bead thereof, and is there held by the spring wire 12.

60 Obviously, the piston groove 9 may or may not be used in conjunction with the barrel side vent 7 of Fig. 6 or the similar vent 14 in Fig. 11. In case said groove 9 is used, as is illustrated in Fig. 11, the piston 4 may be 65 driven past the vent aperture 14, as shown,

and then may be rotated, to turn the slot 9 away from said vent 14, thereby preventing leakage when the syringe is inverted, and thus making the operation of filling the barrel and starting the piston less exacting 70 even than in the previously described forms.

I claim:

1. A syringe of the type described, comprising a piston, a barrel therefor having a 75 stabilizing portion for the entering piston extending beyond the upper limit of its solution content, said stabilizing portion having a vent for the escape of air driven therefrom by said piston as it enters.

2. A syringe of the type described, comprising a piston, a barrel therefor having a stabilizing portion for the entering piston extending beyond the upper limit of its solution content, said stabilizing portion having 80 a vent for the escape of air driven therefrom by said piston as it enters, and a guard member carried by the barrel and pressing on the piston to hold it in said stabilizing portion.

3. A syringe of the type described comprising a piston, a barrel therefor having a stabilizing portion for the entering piston extending beyond the upper limit of its solution content, said stabilizing portion having 85 a vent in its wall for the escape of air driven therefrom by said piston as it enters; and a guard member carried by the barrel and pressing on the piston through said vent to hold said piston stable in said portion.

4. A syringe of the type described comprising a piston, a barrel therefor having a stabilizing portion for the entering piston extending beyond the upper limit of its solution content, said stabilizing portion having 90 a vent in its wall for the escape of air driven therefrom by said piston as it enters; and a guard member carried by the barrel and pressing on the piston through said vent to hold said piston; and a finger guard member embracingly fitted upon said portion and connected with said guard member.

5. In a syringe of the type described, a barrel, and a rotatable and longitudinally movable piston cooperating therewith, said barrel, beyond the upper limit of its solution content, provided with a stabilizing portion for said piston and having a vent beyond the upper limit of its solution content for the escape of air driven from the barrel by said piston, and said piston having a longitudinally disposed groove extending upwardly from its entering end and adapted to be moved into and out of registry with said vent by the rotation of said piston within said barrel.

In testimony whereof I have signed my name to this specification.

GEORGE N. HEIN.
